UNITED STATES PATENT OFFICE.

OTTO WINKLER, OF CÖPENICK, GERMANY, ASSIGNOR TO GENERAL ELECTRIC COMPANY, A CORPORATION OF NEW YORK.

MIXTURE-REGULATOR.

1,086,112.

Specification of Letters Patent.

Patented Feb. 3, 1914.

Application filed October 19, 1907. Serial No. 398,165.

To all whom it may concern:

Be it known that I, OTTO WINKLER, a subject of the Emperor of Germany, residing at Cöpenick, Germany, have invented 5 certain new and useful Improvements in Mixture-Regulators, of which the following is a specification.

This invention relates to internal combustion engines and its object is to provide 10 means for regulating the quantity of the explosive charge and for effecting a better regulation of the proportions of air and fuel in said charge under different operating conditions. Ordinarily the quantity of air 15 depends upon the speed of the engine and the strength of the spring which tends to keep the air inlet valve closed, the suction being stronger at higher speeds and the valve opening more widely at such times. 20 But the spring must be very sensitive to respond to slight variations in suction and this entails certain difficulties in operation for any length of time.

In order to avoid these difficulties the 25 present invention consists of an air inlet valve controlled by a mechanical governor responsive to speed variations and other parts coöperating therewith to produce the desired results as set forth more fully in the 30 following description and claims.

The accompanying drawing is a sectional and diagrammatic view of one form of my invention.

The casing 1 has an inlet 5 for air and an 35 outlet 4 for delivering the combustible mixture to the engine through a suitable connection, the movement of the fluid being effected by the suction action of the piston. Within the casing are two cylinders 13 and 40. 14 with their adjacent inner ends joined by a larger cylindrical member 18 communicating with the outlet 4, the upper portions of the cylinders merging with the wall of the casing. The outer ends of the cylinders 45 are separated from the end walls of the casing by passages or openings 16 and 17. Passages 51 and 52 are formed between the outer walls of the cylinders 13 and 14 and the wall of the casing, said passages 50 branching in opposite directions from the inlet 5 so that air can flow through them toward the ends of the casing, then through the openings 16 and 17 into and through said cylinders to the outlet 4. Thus there 55 are two flow paths or conduits connecting

the inlet with the outlet. The flow through the two conduits is controlled or regulated by the tubular slide valves 2 and 3. The valve 2 is mounted in the cylinder 13 and has a rod 7 connected to it for adjusting it 60 to vary the effective opening of the outlet 4, said valve thus constituting the throttle valve of the engine. The valve 3 is mounted in a sleeve 15 arranged in the cylinder 14 but cut away at its outer end so as not to 65 obstruct the passage 16. The diameter of the valve 3 is such that it can be moved into telescopic relation with the interior of the valve 2 if desired. The adjacent ends of the valves are notched so as to secure a 70 further regulation of the flow opening between them. The valve 3 is connected by a rod 8 with a centrifugal governor such, for example, as the rotating ball governor 9 mounted on the shaft 10, driven by the 75 engine, and actuating the rod 8 through a sliding sleeve 11 and a lever 12. As shown, the governor parts are at or near their full speed position.

A nozzle 6 passes through the casing and 80 the wall of the cylinder 13 into the interior of the valve 2 and is connected with a supply tank or chamber in which a constant level of gasoline or other fuel is maintained. The air entering the inlet 5 divides into two 85 streams and the left-hand stream is carbureted by fuel from the nozzle 6 as it flows past said nozzle. The other stream flows through the right-hand conduit and as it leaves the valve 3 it mixes with the carbureted air coming through the valve 2. When 90 the speed is low, the governor balls are drawn toward each other by the connecting spring and the valve 3 is moved toward the end of the casing partially or wholly shutting off the flow through the right-hand path or conduit and thereby cutting down or throttling the supply of pure air so that the mixture leaving the outlet 4 is richer in fuel. Assuming the valve 3 to be at or near 95 its extreme right position, as the engine speeds up the governor moves the valve to the left permitting a greater flow of air so that the mixture becomes relatively weaker. Furthermore, as the left end of the valve 3 100 approaches nearer the end of the valve 2 it acts to throttle the quantity of mixture passing to the outlet 4. If the valve 2 is adjusted by hand or by suitable means to admit just enough mixture to keep the engine 105 110

running at a given speed, then the valve 3 will act as a governor valve to maintain the speed constant as the load varies. If the speed tends to increase, the valve 3 will be moved by the governor toward or even into the valve 2, thereby cutting off the flow of mixture to a greater or less degree, while if the speed slackens, the valve 3 will be moved to the right and permit a larger quantity of mixture to flow. The governing movements of the valve 3 are not sufficient, however, to greatly affect the area of the outlet 4 when the throttle valve 2 is drawn to the left so far as to permit the predetermined maximum flow corresponding to the full output of the engine.

Viewed in one way the inner end of the valve 3 forms a seat for the valve 2, while the inner end of the valve 2 performs the same office for the valve 3. By reason of this arrangement, a movement of either valve, the other remaining stationary, will control the passage of the mixture to the outlet 4. Movements of both valves toward or away from each other will effect an increase or decrease in the fuel supply very quickly as is sometimes necessary. Furthermore, the arrangement described results in a very simple and compact apparatus and one in which the cooperative parts are located close together in the same casing. Another advantageous feature resides in the fact that the pure air discharged through the valve 3 is, so to speak, projected into the mixture passing through the valve 2 and is thereby caused to thoroughly and intimately mix therewith.

What I claim as new and desire to secure by Letters Patent of the United States, is:—

1. In a mixture regulator for internal combustion engines, the combination of a casing having an inlet and oppositely disposed branch conduits communicating therewith, an outlet conduit communicating with the branch conduits, a valve located in one of the branches and controlling the passage of air therethrough, means for carbureting the air flowing through the other branch conduit, and a valve located in the second branch conduit by which the flow of carbureted air to the outlet conduit is controlled, said valves being located end to end and arranged to move toward and away from each other to regulate the amount of combustible mixture flowing through the outlet.

2. A mixture regulator for an internal combustion engine, comprising an inlet pipe having oppositely disposed branches leading therefrom to a junction, a conduit leading from the junction of the branches to the engine cylinder, a valve in one branch for regulating the flow of air therethrough, said valve having a portion adjacent said junction that is movable to regulate the effective area of the inlet opening of said conduit, a

speed responsive device connected with the valve for moving it, means for carbureting the air flowing through the other or second branch, and a manually controlled throttle valve in the second branch having a portion adjacent said junction that is movable to regulate the effective area of the inlet opening of the conduit, the combustible mixture passing between the opposed faces of said portions of the two valves to said conduit.

3. A mixture regulator for an internal combustion engine, comprising a casing having an inlet pipe and oppositely disposed branches leading therefrom to a junction, one of said branches having two parallel portions with a common wall between them and a passage in the wall that connects the two portions, a conduit leading from the junction of the branches to the engine cylinder, a tubular valve coöperating with said passage to control the flow of air through said branch, a speed responsive device connected with said valve for moving it to control the flow, a tubular throttle valve in the other branch, the ends of said valves being opposed and the combustible mixture flowing between them to said conduit, and means for carbureting the air flowing through the throttle valve.

4. A mixture regulator for an internal combustion engine, comprising a casing having an inlet and oppositely disposed branch conduits having parallel portions provided with lateral connecting openings, an outlet leading from the junction of the branches, a tubular valve coöperating with one of said openings to control the flow of air through one branch, a speed responsive device connected with said valve for moving it, a tubular throttle valve in the other branch, said valves having opposed ends arranged adjacent the junction, the mixture flowing between said ends to the outlet and the valves being constructed and arranged to telescope one within the other to thereby vary the flow to the outlet as the first valve moves under the action of the speed responsive device, and means for carbureting the air flowing through the throttle valve.

5. The combination with an internal combustion engine, of an air inlet pipe having branch portions with axially aligned sections provided with inlet openings at their outer ends and an opening at the junction of said sections, a conduit leading from the opening at said junction to the engine cylinder and having its axis transverse to the axis of said sections, a tubular throttle valve movable longitudinally in one section to overlie the junction opening to a greater or less extent, means for manually operating the throttle valve to vary the effective area of the opening at the junction, a device for carbureting the air flowing through the throttle valve, a tubular valve in the oppo-

- site section through which air flows to said opening at the junction, said valve being movable longitudinally to overlie the inlet and junction openings, and a speed responsive device for moving the last mentioned valve axially to vary the space between the adjacent ends of the valves to thereby vary the effective area of the opening at said junction and also to vary the effective area 10 of the inlet to said section.
6. In a mixture regulator for internal combustion engines, in combination with a casing having an inlet, an outlet and connecting passages, a hollow valve in the casing through which the mixture flows in one direction, a second hollow valve also located in the casing and through which air flows in the opposite direction, said valves being on opposite sides of the outlet and presenting 15 opposed ends between which combustible mixture and air flow from opposite directions to the outlet, means for carbureting the air passing through the mixture valve, and means for moving the mixture valve, and 20 means for moving the air valve independently of the mixture valve to control the distance between the ends of the valves.
7. In a mixture regulator, the combination with a casing containing an inlet, an outlet and passages through which a combustible mixture and pure air flow, said passages being so disposed that the mixture and air flow toward each other from opposite directions, hollow valves in said pas- 25
- sages through which the mixture and air flow, said valves having opposed ends adjacent to said outlet that coöperate to control the flow of combustible mixture through the space between them, and a mechanism whereby either valve can be moved toward or away from the other to control the flow of combustible to the outlet. 35
8. In a mixture regulator, the combination of a casing, two axially aligned cylinders in the upper part of the casing, the upper portion of whose walls merge with the wall of the casing, there being passages between the outer ends of the cylinders and the end walls of the casing, a cylindrical member 40 that unites the inner ends of the cylinders and has an outlet leading therefrom through the wall of the casing, an air supply conduit connected to the interior region of the casing between the cylinders and the casing walls, tubular valves in the cylinders 45 having their ends movable into and out of the cylindrical member to vary the distance between said ends, means for moving the valves relatively to each other in an axial direction, and a device for carbureting the 50 air that passes through one of the valves. 55

In witness whereof, I have hereunto set my hand this fifth day of October, 1907.

OTTO WINKLER.
